SUPERCHARGER CONTROL

Kenneth A. Browne, Fairlawn, N. J., assignor to
Wright Aeronautical Corporation, a corpora-
tion of New York

Application May 14, 1941, Serial No. 393,331

18 Claims. (Cl. 230—114)

This invention relates to centrifugal blowers and is particularly concerned with improvements in such blowers by which efficient operation thereof may be attained over a wide speed range and over a wide range of load coefficient.

An object of the invention is to provide an adjustable diffuser, embracing a blower impeller, by which the angle of the diffuser vanes may be altered during operation. A further object is to provide means for sealing the adjustable diffuser vanes against side leakage while an associated object is to provide a member forming one side of the diffuser passages which may be movable into and out of engagement with the sides of diffuser passages which may be movable into and out of engagement with the sides of diffuser vanes for the dual purpose of sealing the vanes and for clamping them against movement when they are adjusted to a position appropriate to a certain order of blower delivery. A further object is to provide automatic means for adjusting diffuser vanes which is responsive in its operation to the load coefficient under which the blower may be operating.

Still another object is to provide a servo control system which shall be coincidentally operable to unclamp the diffuser vanes for adjusting movement and to move the vanes to a new position of adjustment, after which reclamping and sealing of the diffuser vanes may take place.

Centrifugal compressors or blowers obtain their highest adiabatic efficiency over a relatively narrow band of load coefficient which may be represented by the expression Q/N , which represents the cubic feet of inlet air per impeller revolution, and the narrow efficiency band is positioned relative to Q/N primarily by the angular setting of the diffuser vanes surrounding the impeller. Where fixed vanes are used, a narrow band of high efficiency is unfavorable where the compressor has to operate at various Q/N values as is the case of superchargers for internal combustion engines, particularly where the supercharger has several drive ratios as in the case of a multi-speed mechanically driven supercharger, or in the case of an exhaust turbine driven supercharger which has a wide range of impeller speed with respect to engine air demand. Consequently, the fixed vane superchargers are designed to increase the band width at the expense of peak efficiency so that reasonable efficiencies are obtained under the actual operating conditions. Variable angle diffuser vanes will allow of maximum obtainable efficiency over a wide range of Q/N . To construct a satis-

factory variable angle diffuser, the vanes may be individually pivoted to a back plate and they may be jointly adjusted in their angular relation by a ring either linked to or having a slotted connection with the several diffuser vanes. In the present invention, I contemplate using the latter mode of diffuser vane adjustment and in addition, utilize the master adjusting ring as a side plate for the diffuser assembly, this side plate being axially movable to clamp the vanes from vibratory movement when no adjustment is in process, and furthermore, by clamping the plate against the sides of the diffuser vanes, interflow between diffuser passages is substantially prevented, avoiding the loss of efficiency which would occur as a result of leakage between the passages, and I further compensate for manufacturing tolerances in the assembly by this expedient.

20 In the control of diffuser vane adjustment, I utilize a servomotor which is responsive to changes in Q/N . This character of adjustment is obtained by making the servomotor control responsive to changes in pressure rise across part 25 of the impeller along with changes in the velocity of flow of the medium into the impeller eye.

Furthermore, I coordinate the operation of the clamping and adjusting ring with the vane adjusting servomotor in such fashion that vane ad- 30 justments are accompanied by a preliminary re-lease of the clamping ring and a subsequent re-clamping of the ring against the sides of the diffuser vanes.

Further objects of the invention, and a clearer 35 understanding of the provisions thereof will be obtained by reviewing the drawing in connection with the detailed description below.

In the drawing, 10 represents a rotary impeller 40 embraced by a housing 11, part of which forms an axial impeller intake eye 12 blending into an impeller shroud 13. The impeller delivery is substantially radial, and delivers air or other fluid medium substantially radially and tangentially into an exit duct 14 through a vaned dif- 45 fuser 15. The latter comprises a plurality of circumferentially spaced diffuser vanes 16 pivotally mounted for angular adjustment on pivot pins 17 secured in the housing 11. Each vane 16 carries a pivoted block 18 spaced from the pivot 50 pins 17 engaged in a substantially radial slot 19 in a clamping and adjusting ring 21 which is loosely piloted at 22 on the outer rim 23 of the shroud section of the housing 11, the ring 21 being ar- 55 ranged for slight axial movement and for slight circumferential movement. In virtue of the

axial movement of the ring 21, it may be moved leftwardly into clamping engagement with the righthand side faces of the diffuser vanes 16, securing the side faces of the vanes and clamping them against inadvertent angular movement on their pivots 17. Axial movement of the ring 21 toward the right frees the vanes for adjusting movement and by subsequent rotational adjustment of the ring 21, the angular position of the vanes 16 is altered.

To afford the rotational adjustment of the ring 21, I provide a shaft 25 having a crank 26, said shaft being carried in a rigid bearing, not shown. The inner end of the shaft carries a dog 27 engaging a notch 28 in the ring 21 so that, by turning the crank 26, limited rotational adjustment of the ring 21 is secured.

As will be seen in the lower part of the figure, the ring 21 defines with the housing portion 23 an annular cavity 30 which under normal operating conditions will be under supercharger discharge pressure by leakage of the pumped fluid through the clearance at 22 or through apertures 31 in the housing element 23. The inner edge of the ring 21 is sealed to the outer rim of the shroud 13 by a suitable elastic gasket 32. The housing is provided with an annular chamber 33 communicating with the cavity 30 through drillings 34 whose aggregate area is somewhat greater than the leak area at 22 so that, by dumping the cavity 33 through the medium of a valve 36 vented to atmosphere at 37, pressure within the cavity 30 is relieved, thereby driving the ring 21 to the right in virtue of the intermediate pressure, greater than atmospheric but less than supercharger discharge, residing in the diffuser section 15. Thus, when the valve 36 is opened, the ring 21 frees the vanes 16 and subsequent rotational adjustment of the ring by the crank 26 alters the diffuser vane setting. Upon closing of the valve 36, supercharger pressure again builds up in the cavities 30 and 33 to move the ring 21 leftwardly into clamping and sealing engagement with the side faces of the vanes 16.

In order to prevent slamming of the ring 21 to the right, the outer surface of the ring 21 is provided with pads 39 overlying the drillings 34 so that as these pads approach abutment with the housing section containing the drillings 34, flow of air from the cavity 30 is throttled and an air cushion is formed to prevent contact of the ring with the housing.

To automatically control adjustment of the diffuser vanes, I provide a servomotor 40 which comprises a cylinder 41 containing a piston 42, the piston being directly connected to the crank 26 by a link 43. The piston rod extends to the right as at 44 beyond the cylinder end and to it is secured a lever fulcrum 45 through which passes a lever 46. The left end of the lever 46 is clevised to a servo valve 47 whose lower end is secured to a diaphragm 48 which divides the diaphragm chamber into an upper cavity 49 and a lower cavity 50. The cavity 49 connects through a pipe 51 to the supercharger impeller cavity through the shroud 13 while the lower cavity 50 connects through a pipe 52 to the supercharger inlet whereby the diaphragm, and consequently the valve stem 47 and the left end of the lever 46 are subjected to a force proportional to the pressure rise across part of the impeller.

The right end of the lever 46 is pivoted on a stem 54 connected to a diaphragm 55 which divides its housing chamber into an upper cavity 56 and a lower cavity 57. The cavity 56 con-

nects through a pipe 58 to a Pitot tube 59 in the impeller eye while the lower cavity 57 connects through a pipe 61 to the throat of a venturi 62 disposed in the impeller eye. Thus, the force acting upon the diaphragm 55, and consequently upon the stem 54 and the righthand end of the lever 46, is proportional to the intake velocity of the supercharger.

The servo valve stem 47 upon vertical adjustment thereof, admits pressure fluid from a suitable source through a line 64 to either the right or lefthand ends of the cylinder 41, the left or right hand ends of the cylinder, respectively, being concurrently connected through the servo valve 47 to the interior of the servomotor 40 for subsequent drainage through a conduit 66. When the piston 42 and the diffuser vanes are fixed in position, the moments about the adjustable fulcrum 45 of the lever 46 must be equal. When any material change occurs in the blower pressure rise or in the velocity of flow into the impeller, an unbalance will obtain, changing the position of the servo valve 47 to admit pressure fluid to one side or the other of the piston 42, urging change in adjustment of the diffuser vanes. Such change in adjustment will of course change the position of the fulcrum 45 which in effect acts as a balancing follow-up to secure a new equilibrium position for the servo motor, the attainment of such position of course centralizing the valve 47 and cutting off motive fluid flow to the cylinder 41.

The motive fluid feed passages 68 and 69 which establish connections respectively between the righthand end of the cylinder 41 and the valve 47, and the lefthand end of the cylinder 41 and the valve 47, are bridged by a cavity 71 having restricted communication at its ends with the passages 68 and 69. This cavity 71 is connected, by a conduit 72, to a cylinder 73 having therein a piston 74 acting upon the valve 36 which is normally urged to a closed position by a spring 75. Admission of pressure fluid to the cylinder 73 will move the piston 74 leftwardly to open the valve 36 while relief of pressure from the cylinder 73 will allow closing of the valve 36. Such opening and closing of the valve 36, as indicated previously, serves to unlock and lock the ring 21 respectively to allow of adjusting movement of the diffuser vane 16. Pressure in the line 72 is imposed as soon as the servo valve 47 moves in either direction to admit pressure fluid to the cylinder 41 so that as such pressure is imposed, the first resulting function will be to unload the diffuser clamping ring 21 after which the piston 42 may effect diffuser vane adjustment. When such adjustment is attained, the pressure on opposite sides of the piston 42 will equalize and there will be no flow through the cavity 71 and furthermore, the valve 47 will close and the pressure downstream of the valve 47 will drop to allow of relocking of the diffuser vane clamping ring 21.

The source of operating oil pressure for the servomotor 40 (serving the conduit 64) is not shown but it is obvious that such motive pressure may be secured from a reservoir or pump of suitable character. When the blower system is associated with an internal combustion engine to form a supercharger therefor, engine lubricating oil pressure may be utilized as a source of motive pressure for the servomotor 40.

It will be seen that the servomotor 40 is cognizant of the ratio Q/N and it shifts the diffuser vanes automatically as dictated by the operating

load coefficient. The optimum position of the vanes 16 is directly proportional to the value Q/N and therefore the control should move the vanes linearly with respect to Q/N . In the figure, the diaphragm 55 is sensitive to the pressure differential created in the pitot-venturi 59, 62. The diaphragm 48 is sensitive to the pressure differential created by impeller rotation. The diaphragms 55 and 48 are linked to the ends of the lever 46 provided with the movable fulcrum 45, the fulcrum being movable in accordance with movements of the piston 42.

The pitot-venturi 59, 62 is a device which produces a pressure differential proportional to DV^2 where D is the density of the air surrounding the venturi and V is its velocity. Obviously, Q is directly proportional to V and consequently the pressure differential P_v imposed on the diaphragm 55 is proportional to DQ^2 whereby Q is proportional to the square root of P_v/D .

Neglecting the friction loss in flow of air through the impeller passages, the rise in pressure P_c through a fixed increment of the impeller varies directly as DN^2 wherefore N is proportional to the square root of P_c/D . It follows directly that Q/N is proportional to the square root of P_v/P_c . Now, the shifting fulcrum for the lever 46 produces a control effect which is not a linear function, but it turns out that this shifting fulcrum device when combined with the control forces proportional to Q^2 and N^2 produces a nearly linear control effect on the vanes within the useable range both of fulcrum position and the Q/N ratio.

In operation, the forces from diaphragms 55 and 48 must be in balance about the fulcrum 45; otherwise, the servo valve 47 will move to admit oil to the cylinder 44 causing it to move the fulcrum 45 to a point creating balance of the forces on the diaphragms 55 and 48. The type of diaphragm shown in the figure does not have a constant piston area. This area increases with rise in the diaphragm and decreases with drop; consequently stability at the balance point is obtained inherently. If this stabilizing effect is inadequate, a spring may be added at the diaphragms which will urge the servo valve 47 to mid position. A definite overlap of valve closure is provided in the servo valve 47 to prevent continual movement and hunting of the control.

The ports adjacent the cavity 71 are so arranged that oil pressure acts on the piston 42 prior to its action in the cavity 71 and on the piston 74. At all times when the forces in the diaphragms 55 and 48 are balanced, no oil flow exists through the servo valve 47, and the vent valve 36 remains closed.

Preferably, by the proper empirical adjustment of the linkage between the piston 42 and the diffuser vanes 16, the latter are automatically positioned to give maximum efficiency from about 35% to about 120% of the rated air flow through the blower. This range of adjustment will take care of all normal running conditions of the blower when used as an engine supercharger.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. In a centrifugal blower comprising a hous-

ing, an impeller rotatably mounted therein and diffuser vanes disposed about the impeller periphery, means mounting said vanes for angular movement, an operator for moving said vanes jointly, and means movable against said vanes to secure said vanes against inadvertent movement when said operator is inactive, said movable means comprising a releasable ring clampable into engagement with all said vanes.

2. In a centrifugal blower, a housing comprising a diffuser plate having circumferentially spaced pivots, a diffuser vane mounted on each pivot, a ring mounted for rotational adjustment relative to said plate with the diffuser vanes disposed between said ring and plate, a sliding connection between said ring and each vane, each said connection being spaced from the pivot of the corresponding vane, whereby rotational ring adjustment affords joint adjustment of the angular position of the vanes upon said plate, and means to move said ring axially into and out of clamping engagement with said vanes.

3. In a centrifugal blower having adjustable diffuser vanes, a member for adjusting the vanes jointly, a servomotor for actuating said member, a servo valve operable to control flow of operating fluid to and from the motor, means for operating said valve responsive to pressure rise across the blower and to rate of flow through the blower, a locking ring for the diffuser vanes, and means responsive to valving of fluid to and from the motor to unlock said ring.

4. In a centrifugal blower having adjustable diffuser vanes, a member for adjusting the vanes jointly, a servomotor for actuating said member, a servo valve operable to control flow of operating fluid to and from the motor, means for operating said valve responsive to pressure rise across the blower and to rate of flow through the blower, an axially movable ring on one side of the diffuser vanes and adapted, when bearing on the vanes, to clamp them from inadvertent movement, an annular cell of which said ring forms a wall the cell having restricted communication with the blower discharge whereby blower discharge pressure acts upon said ring to hold it in clamping engagement with said vanes, a dump valve in said cell to unload the blower discharge pressure therefrom, and means responsive to operation of said servo valve to open said dump valve.

5. In a blower having a variable speed impeller, means to maintain blower efficiency at a high level over a wide speed range comprising concurrently tiltable diffuser vanes disposed around the impeller exit openings, means to tilt said vanes, a clamp normally holding said vanes in fixed position, and means responsive to initiation of operation of said tilting means to release said vane clamp to allow of free movement of said vanes said clamp being actuated by fluid under blower delivery pressure and said releasing means comprising a device for dumping that fluid which operates said clamping means.

6. In a supercharger, an impeller, a backplate, diffuser vanes pivotally mounted on said backplate, a ring opposite said backplate with the diffuser vanes disposed between said ring and backplate, rotatably and axially movable relative to the backplate, a connection between each vane and said ring whereby ring rotation changes diffuser vane tilt, and means to move said ring axially into clamping and end-sealing engagement with said vanes.

7. In a supercharger, an impeller, a backplate,

diffuser vanes pivotally mounted on said backplate, a ring opposite said backplate, rotatably and axially movable relative to the backplate and with the diffuser vanes disposed between said ring and backplate, a connection between each vane and said ring whereby ring rotation changes diffuser vane tilt, means to move said ring axially into clamping and end-sealing engagement with said vanes, and automatic control means operable sequentially to unclamp said ring, to rotate said ring and to reclamp said ring.

8. In a supercharger, an impeller, a backplate, diffuser vanes pivotally mounted on said backplate, a ring opposite said backplate, rotatably and axially movable relative to the backplate, a connection between each vane and said ring whereby ring rotation changes diffuser vane tilt, means to move said ring axially into clamping and end-sealing engagement with said vanes, and control means operable sequentially to unclamp said ring, to rotate said ring and to reclamp said ring, said control means being responsive in its operation to changes in the blower delivery per impeller revolution.

9. In a supercharger, an impeller, variable angle diffuser vanes around the impeller, a bellows device subject to rise in pressure between the impeller intake and a point on the impeller upstream of the diffuser vanes, a bellows device subject to a pressure proportional to flow through the supercharger, a beam connecting said bellows, a movable fulcrum for said beam, means for moving said fulcrum in accordance with diffuser vane tilt, and means operated by beam movements to vary the diffuser vane angles concurrently.

10. In a supercharger, an impeller, variable angle diffuser vanes disposed around the impeller, a means controlled by impeller speed, a means controlled by supercharger flow, a device actuated by said two means to alter the diffuser vane angle, and follow-back mechanism operated by the diffuser vanes to stabilize the control effect of said two means.

11. In a supercharger having variable angle diffuser vanes, means to vary the angle of said vanes, a clamp member movable into vane engagement to clamp the vanes against movement, pressure responsive means to urge said vanes to a new position, and means responsive to incipient operation of said pressure responsive means to disengage said clamp member from said vanes.

12. In a supercharger, an impeller, a variable

vane diffuser; a servomotor for varying the vanes including an operating valve, means to move said valve in response to changes in the blower delivery per impeller revolution, a clamp for said vanes, and means responsive to initiation of servomotor operation to release said clamp, and to stopping of the servomotor to apply said clamp.

13. In a blower comprising a housing, an impeller rotatably mounted therein and diffuser vanes disposed about the impeller periphery, means mounting said vanes for angular movement, means movable in one direction for adjusting said vanes and movable in another direction for securing said vanes against inadvertent movement.

14. In a blower, a housing, an impeller rotatably mounted therein, pivotally mounted diffuser vanes disposed about the impeller periphery, and a member movable to adjust said vanes and upon completion of an adjustment movable to secure said vanes against inadvertent movement.

15. In a blower, an impeller, adjustable diffuser vanes mounted between two opposed walls, and means to adjust said vanes, one of said walls being axially movable into clamping and end sealing engagement with said vanes when said vanes are not being adjusted.

16. In a blower, an impeller, adjustably movable diffuser vanes mounted between two opposed walls at the impeller outlet, means to move at least one of said walls into clamping and end sealing engagement with said vanes to lock said vanes against movement, and means automatically responsive to variations in blower performance and operable sequentially to effect unclamping of said vanes, adjustment of said vanes and reclamping of said vanes against adjustment.

17. In a blower, an impeller, variable diffuser vanes at the impeller outlet, means responsive to fluid flow through the impeller, means responsive to the pressure differential across a portion of the impeller upstream from its outlet end, and control mechanism operated by said two means to adjust said vanes.

18. In a blower, an impeller, variable diffuser vanes at the impeller outlet, means responsive to the pressure differential across a portion of the impeller upstream from its outlet end, and control mechanism responsive to said means for adjusting said vanes.

KENNETH A. BROWNE.
